(57) **CLAIM**

The ornamental design for a golf bag, as shown and described.

DESCRIPTION

FIG. 1 is a first perspective view of a golf bag showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 2; and,

FIG. 10 is an enlarged view of the selected portion 10 in FIG. 2.

The even dash broken lines shown in the drawings depict portions of the golf bag that form no part of the claimed design. The uneven dash broken lines indicate the boundaries of the enlarged view and form no part of the claimed design.
